(57) **CLAIM**

The ornamental design for a display screen with graphical user interface, as shown and described.

DESCRIPTION

The file of this patent contains at least one drawing executed in color. Copies of this patent with color drawings will be provided by the United States Patent and Trademark Office upon request and payment of the necessary fee.

FIG. 1 is a front view of a first image of a display screen with graphical user interface showing our new design in a first embodiment;

FIG. 2 is a front view of a second image thereof;

FIG. 3 is a front view of a third image thereof; and, FIG. 4 is a front view of a fourth image thereof.

The appearance of the graphical user interface sequentially transitions between the images shown in FIGS. 1-4. The process or period in which an image transitions to another forms no part of the claimed design.

The broken line rectangle showing the display screen and the broken lines showing the graphical user interface illustrate portions of the display screen with graphical user interface that form no part of the claimed design.
